his ATTORNEYS.

UNITED STATES PATENT OFFICE.

TENISON DEANE, OF SAN FRANCISCO, CALIFORNIA.

TELEPHONE REST.

Refiled for abandoned application Serial No. 734,541, filed August 27, 1924. This application filed March 29, 1927. Serial No. 179,126.

This invention relates to telephones and in particular to what is known as a desk-phone, that is, a portable telephone transmitter provided with a base for standing on a desk or 5 table and with a receiver removably hung on a hook at the side of the instrument and which must be removed and held to the ear when receiving a message, all as well known.

The objects of my improvements are to 10 provide a simple cheap wire device which is supported on the transmitter stand and which will afford a support for the receiver when removed from the hook so that it will not be necessary to hold it by hand to the 15 ear.

Also such a device which may easily be adjusted to different positions on the supporting instrument, and one which may be quickly attached or detached from the supporting instrument without the aid of 20 screws, clamps or other securing means.

This application is to take the place of my former informal application filed under Ser. No. 734,541, Aug. 27, 1924.

25 In the drawings hereto Fig. 1 is a perspective view of my device in place on a portable telephone instrument, the telephone instrument being shown in dotted lines, while Fig. 2 is a reduced size plan view of 30 the device unattached to the telephone.

In further detail the device comprises a pair of spaced wire arms 1 and 2 formed respectively with reversely directed open hooks 3 and 4 which are adapted to embrace 35 from reverse sides the column 5 of a desk telephone instrument, each hook being covered with a short section of rubber tubing 3'-4' so as to get a slight frictional hold upon the column and also lessen any tendency of noise 40 to be transmitted from the telephone or table, upon which it may stand, to the arms.

The arm 1 extends at an upward angle from the instrument and is joined at 6 by arm 2 which diverges downwardly to the 45 point A thence continues downwardly substantially parallel and spaced from the column 5 a distance B to afford clearance for the hand in holding the column of the instrument.

50 At the point 6 the arm 1 is bent to extend

laterally as at 7 terminating in an inverted arch portion 8 extending at right angles thereto, thence extending divergingly opposite 7 as at 9 and terminating in another inverted arch portion 10 somewhat larger 55 than the arched portion 8, and joining the upper end of arm 2 after taking a wrap around run 7.

The reversely open hooks 3 and 4 are aligned when viewed in plan as shown in 60 Fig. 2 and the lower one 4 is adapted to rest upon the telephone instrument adjacent the juncture of the column 5 and base 11 so as to sustain the weight of the receiver 12 of the instrument when the same is placed horizontally upon the inverted arch portions 8 and 10 (as shown in dotted lines). The arched portions 8 and 10 are so spaced as to form a cradle for the receiver while the runs of wire 7 and 9 help to hold the receiver 70 from accidental displacement.

When the receiver is placed in the basket formed by the wires, 7, 8, 9, 10 it lies in a substantially horizontal position so that a person holding the instrument in one hand 75 by the column 5 and speaking into the transmitter 13 will find the end of the receiver 12 in position adjacent the left ear, and owing to the freedom of the wire bracket to revolve about the column 5 the receiver may 80 be revolved with it to any angular position desired and also by reason of the bracket being made of wire members converging to a juncture at 6 the cradle or basket portion holding the receiver 12 may be bent from 85 point 6 to just the proper angle, up, down, or laterally, to suit the individual requirements.

In use as shown, the weight of the receiver 12 presses downward upon the end of the 80 bracket thus pulling forward on the upper hook 3 and pushing backward on the lower hook 4, and stabilizing the bracket, tho when desired, by a reverse pressure applied to the reversely open hooks the bracket may be 85 quickly detached from the standard or column 5 of the telephone instrument.

I claim:

A telephone rest adapted to fit a telephone 90 of the desk type formed of a single piece 100

of continuous wire bent near the middle portion to loosely hold a receiver in fixed relation to the transmitter in a substantially horizontal position suitable for hearing, the ends of said wire sloping downwardly away from said receiver towards the column of said telephone transmitter and formed with

hooks for engaging said column, one of said hooks engaging the column at the top and shaped to take tension, the other of said hooks engaging the column at the bottom and shaped to take compression. 10

TENISON DEANE.
